US00D975192S

(12) **United States Design Patent** (10) **Patent No.:** **US D975,192 S**
(45) **Date of Patent:** **** Jan. 10, 2023**

(54) **KIDS SCOOTER**

(71) Applicant: **Guangzhou Bole Industrial Development Company Limited, Guangzhou (CN)**

(72) Inventor: **He Xu, Guangzhou (CN)**

(**) Term: **15 Years**

(21) Appl. No.: **29/786,258**

(22) Filed: **May 31, 2021**

(51) **LOC (14) Cl. 12-11**

(52) **U.S. Cl.**

USPC **D21/423**

(58) **Field of Classification Search**

USPC D21/419, 421, 423, 760, 763, 765, 771; D12/1, 8, 107, 110, 112-114

CLAIM

The ornamental design for a kids scooter, as shown and described.

DESCRIPTION

FIG. 1 is a first perspective view of a kids scooter showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines showing of the article depict portions of the kids scooter and form no part of the claimed design.

1 Claim, 8 Drawing Sheets
